US0D1108505S

(12) **United States Design Patent** (10) **Patent No.:** **US D1,108,505 S**
(45) **Date of Patent:** **** Jan. 6, 2026**

(54) **WORKSTATION FOR HANDLING GOODS**

(71) Applicant: **BEIJING GEEKPLUS TECHNOLOGY CO. LTD.**, Beijing (CN)

(72) Inventor: **Wei Zhang**, Beijing (CN)

(73) Assignee: **BEIJING GEEKPLUS TECHNOLOGY CO. LTD.**, Beijing (CN)

(**) Term: **15 Years**

(21) Appl. No.: **29/875,721**

(22) Filed: **May 9, 2023**

Related U.S. Application Data

(62) Division of application No. 35/514,544, filed on Feb. 21, 2022 (U.S. filing date under 35 U.S.C. 384), and having an international filing date of Feb. 21, 2022, now Pat. No. Des. 997,217.
